UNITED STATES PATENT OFFICE.

WILLIAM AUGUSTUS HALL, OF NEW YORK, N. Y.

FURNACE.

1,076,763.

Specification of Letters Patent. Patented Oct. 28, 1913.

Application filed October 10, 1912. Serial No. 725,023.

To all whom it may concern:

Be it known that I, WILLIAM AUGUSTUS HALL, a citizen of the United States, and resident of New York, N. Y., have invented 5 a certain new and useful Improvement in Furnaces, of which the following is a specification.

This invention has for its object to provide a furnace for use in decomposing pyrites and metallic sulfids and producing sulfureted hydrogen or (and) sulfur directly therefrom, whereby the sulfids, while in the furnace, may be subjected to the action of steam and of a reducing flame, preferably 15 alternately.

The invention is illustrated in the accompanying drawings in which—

Figure 1 is a part elevation, part vertical section, and Fig. 2 is a horizontal section, of 20 a mechanical furnace fitted with my improvements.

Referring to the drawings, sets of standpipes such as indicated A, A', A² are disposed around the furnace proper, the standpipes A being each supplied, by means of 25 a pipe B, with steam or water vapor from a suitable source; the standpipes A' being supplied, by means of a pipe B', with gas from a gas producer or the like, and the standpipes A² being each supplied with air 30 from a suitable source, as for instance from an air compressor by means of a pipe B². From the standpipes A, pipes C supplying steam or water vapor extend through the 35 furnace wall and terminate in nozzles C'. From the standpipes A' and A² are led pipes D and E for supplying reducing gas and air, respectively, each of said pipes preferably terminating in an extension F which 40 passes into the furnace wall and terminates in a nozzle F'. A group of nozzles C', F' are disposed just above each shelf a of the furnace and are arranged to supply the necessary steam, and the gas and air by ignition 45 of which is produced the necessary reducing flame to act directly on the pyrites or metallic sulfids as they are moved around the shelves by rakes a' or the like. The extension F increases in diameter toward the 50 outer wall of the furnace, as shown, so as to assist in producing an intimate mixture of gas and air. The nozzles F' are also preferably each provided with a wire gauze screen or filter G, and, to permit of easy removal, 55 are arranged to fit loosely in the furnace wall and to be tamped in with clay.

As shown, and as preferred, each pipe E is arranged coaxially of the extension F, while the pipe D meets it at right angles. By this arrangement, the air passing through the pipes E produces an injector-like action 60 on the gas from the standpipe A'. A rotatable diverter H with openings adapted to register with openings on the extension F is provided on said extension for the admission of additional air if desired. 65

The pyrites or metallic sulfids are fed in at I, and, enveloped in the atmosphere of reducing flame and steam, pass around and fall on to successive shelves a, being finally 70 discharged, as at b from the lowermost shelf. The sulfureted hydrogen or sulfur or both together pass off by way of the discharge pipe K.

Valves are fitted at X so as to permit 75 regulation of the amount of steam, gas, and air supplied to the various shelves. By means of properly adjusting these valves, any desired conditions of reductivity of the 80 gases in contact with the ore on the various shelves can be maintained. In practice I prefer to maintain a more highly reducing atmosphere, in the upper compartments than in the lower compartments. By suitable regulation of the air, gas and steam 85 connections, I can produce any desired conditions as to reduction, oxidation or neutrality in this respect, in each of the several compartments into which the furnace is divided, according to the process in which 90 the furnace is to be employed.

By the arrangement above described, the pyrites or metallic sulfids, as they are carried around the shelves a by the rakes a' or the like, may be subjected to the action 95 of steam and of a reducing flame.

It will be understood that where I refer in the claims to water vapor I intend to include steam.

Having described my invention what I 100 claim and desire to secure by Letters Patent of the United States is:—

1. A furnace for decomposing pyrites or metallic sulfids comprising superposed shelves, over which the pyrites or sulfids 105 are caused to travel on their downward course, rotatable stirrers disposed adjacent the shelves, and connections for introducing steam and for introducing gas and air, into each of the several compartments, and 110 independently operable means for regulating the relative amounts of steam, gas and

- air introduced to each of said compartments.
2. A furnace for decomposing pyrites or metallic sulfids comprising superposed shelves, over which the pyrites or sulfids are caused to travel on their downward course, rotatable stirrers disposed adjacent the shelves, and connections for introducing steam and for introducing gas and air, into at least a plurality of the several compartments, and independently operable means for regulating the relative amounts of steam, gas and air introduced to each of said plurality of compartments.
3. A furnace for decomposing pyrites or metallic sulfids comprising superposed shelves, over which the pyrites or sulfids are caused to travel on their downward course, rotatable stirrers disposed adjacent the shelves, connections terminating in the vicinity of and above the shelves for introducing water vapor and gas and air into
- the interior of the furnace, and means for controlling the supply of the steam and of the gas and air to the inlets adjacent the various shelves.
4. A furnace for decomposing pyrites or metallic sulfids comprising superposed substantially horizontal shelves, over which the pyrites or sulfids are caused to travel on their downward course, and connections for introducing steam and for introducing gas and air, into each of the several compartments, and independently operable means for regulating the relative amounts of steam, gas and air introduced to each of said compartments.

In testimony whereof I have signed my name to this specification in the presence of two subscribing witnesses.

WILLIAM AUGUSTUS HALL.
